METHOD OF OPERATING GASEOUS
THERMIONIC TUBES

Montford Morrison, Upper Montclair, N. J.

Application October 28, 1943, Serial No. 507,975

3 Claims. (Cl. 315—237)

1

This invention relates to methods of operating certain gaseous thermionic tubes which have a control electrode, an anode and a cathode, and relates in particular to methods employed in telecontrol circuits and has specific relation to electronic relays.

Among the objects of the invention are: to provide a method of operating an electrode controlled gaseous thermionic tube as a direct current relay; to provide such a method with operational current characteristics which closely parallel mechanical relay operation, to provide in such a method a way that does not necessitate the employment of mechanical contacts, and to provide a method having such objects that is simple and reliable.

In the prior art, gaseous triodes have been used in oscillatory circuits, particularly those referred to as relaxation circuits. In these circuits the plate current is always of a pulsating form and the circuit so operates that the gaseous discharge in the tube is extinguished after each impulse by reason of the plate voltage being reduced and held below the ionization voltage of the tube or by reason of the plate circuit being of an oscillatory character in which the plate voltage may be actually reversed at the end of one half-period of the plate circuit.

I have discovered that gaseous conduction electrode control tubes may be selected and oscillatory circuits so fitted to them that an entirely different operation is achieved.

According to this discovery, I may select a gaseous discharge electrode control tube supplied with a direct current source of power and operating a mechanical relay or other translating device, and by properly fitting the input circuit, including the control grid, to the output circuit including the plate, I provide a method of operation of the said tube whereby the plate current assumes a constant unvarying value so long as the proper input voltage is applied to the control grid and by the removal of this control grid voltage the circuit is set into oscillation in such a way as to extinguish the discharge through the said tube causing the said tube to operate in a manner similar to a direct current relay.

This provides a relay action for a make and break circuit, utilizing direct current and providing an extremely high amplification factor.

Other and further objects will be pointed out and obvious in the reading of the description hereunder, particularly when taken in connection with the drawings in which Figure 1 is an actual working drawing illustrating one embodiment of the invention, and Figure 2 is a graph useful in understanding the operation thereof.

Referring to Fig. 1, 1 is a ground-lead between which lead and lead 2 is supplied a make and break input voltage, common to telegraph cir-

cuits. 3 is a switch which, when closed, bridges the input circuit with a 5000 ohm wire wound potentiometer 4. 5 represents the potentiometer arm which is connected to the grid of a gaseous discharge electrode controlled tube 6, the specific one illustrated being a mercury vapor triode known as "128," and sold by the National Union Radio Corporation of New York in 1936.

The cathode of tube 6 has connected in its grid circuit a 25,000 ohm wire wound potentiometer 7, for biasing the grid of said tube and which potentiometer is bridged by a 22.5 volt battery 8. The plate lead 9 has connected in it as a load, a 120 ohm main line sounder 10, of a standard construction, commonly used by the telegraph companies, and said sounder is shunted by a .25 mf. condenser 11. Plate lead 9 has connected in series with it, a 5000 ohm current limiting resistor 12 which closes the circuit of the 300 volt plate power supply 13. Condenser 14 is connected between the relay 10 and the resistor 12 in the plate circuit and thence to the ground-lead 1 and is a 2 mf. condenser.

The tube 6 may in effect be any of the gaseous discharge electron controlled tubes containing any suitable gas, the only requirement being that it is so selected that its characteristics come within those required for the method of operation hereunder claimed.

The above described circuit in appearance is related to a common gaseous triode relaxation oscillator classification and the discovery herein described relates to the method operating such a circuit in a novel and useful manner.

In order to avoid obscuring the teaching of a practical embodiment of the discovery by generalizing upon the circuit functions, the specific circuit above described will be discussed and the generalities relating thereto will be set forth in the claims hereunder.

It has been known in the art that gaseous triodes are very subject to setting up oscillations when connected in certain types of oscillatory circuits but these oscillations have heretofore been very detrimental to the operation of the tube and if allowed to exist under continued operation they quite often and usually do result in a destruction of the tube cathode due to excessive operation imposed upon the cathode under these conditions.

I have discovered that this tendency to oscillate, if utilized in a method of oscillation whereby the oscillations set up are of a very short duration at only periodic intervals, that the tube is not harmed thereby and further, this oscillatory effect can be utilized to extinguish the gaseous discharge through the tube, thereby providing a novel and useful application for a phenomenon which has heretofore resulted chiefly in the destruction of the operable usefulness of the tube.

If the exact circuit is set up as above described and the potentiometer 7 is set up to a bias sufficient to prevent the voltage source 13 from producing gaseous ionization through the tube and then switch 3 closed to provide sufficient voltage by adjustment of potentiometer arm 5 to cause gaseous discharge through tube 6, and then by opening switch 3 and readjusting potentiometer arm 5, there will be found a not too critical point at which the plate circuit begins to oscillate with the result that the gaseous discharge through the tube is completely extinguished.

Several repeated trials of adjustment may be required, including changing the positions of the potentiometer arms of potentiometers 4 and 7 to find the optimum settings to give the most satisfactory result, but finally a setting will be found for at least one range of temperatures of the gas in tube 6 whereupon closing switch 3, gaseous discharge through tube 6 is initiated, which is constant in value and without oscillations therein and upon the opening of switch 3 the gaseous discharge through tube 6 is extinguished by oscillations set up in the circuit of plate 9.

Referring to Fig. 2, curve 14 represents the constant value of the plate current in lead 9 with a properly adjusted steady state bias which is the algebraic sum of the negative bias acquired through potentiometer 7 and a positive voltage acquired through potentiometer 4, which shows graphically the operation described above. This operation continues to a point 15 on curve 14 at which time switch 3, Fig. 1, is opened, allowing the negative bias to increase to the value 21, Fig. 2. The plate current begins to oscillate in accordance with the graph in Fig. 2, beginning at point 15 with increasing oscillations until the value thereof reaches a point 16, which is twice the value of 14 or thereabouts, and upon the succeeding negative half cycle of the said oscillations, the negative voltage has caused the plate voltage of tube 9 to recede to a point below the ionization voltage of the tube, or in most cases, to an actual negative value at which time the gaseous discharge is extinguished.

The length of time required for the tube to extinguish the gaseous conduction depends entirely upon the frequency of these oscillations and the rate at which they can build up, illustrated in Fig. 2, between lines 18 and 19 as being .002 second, assuming the period of oscillation to be 1000 cycles, as illustrated in the figure.

In actual practice, this period, represented by the distance between 18 and 19, can be made much shorter if and when desired, by properly selecting the frequency at which the tube "oscillates out" and the rate at which the amplitude of the frequency employed in oscillating out, is able to build up.

With this bias set at the value of 21, Fig. 2, in so far as additional oscillations are concerned, it will be appreciated by those skilled in the art, that the tube will not oscillate after the plate current has been once extinguished and therefore this oscillatory condition is present in the tube for only a very short interval of time as compared to the total working time of the tube and therefore does no practical harm to the tube under these conditions.

After the tube has oscillated out at point 17, the plate current remains at zero until switch 3, Fig. 1, is again closed at a later time represented by line 22, Fig. 2, at which time gaseous conduction is initiated through the tube and the 75

plate and current immediately rises to a value 25, shown at Fig. 2, usually with a slight oscillation 24 at the beginning of the period but thereafter continues as a steady current until switch 3 is opened and the tube oscillates out again as before described.

In the claims hereunder, the expression "normal gaseous thermionic tube" is employed to specify the structure of gaseous thermionic tubes to 10 which the methods of this invention are applicable. A normal gaseous thermionic tube is hereby defined to be one in which, after the gas has become ionized, the grid ordinarily has no further effect on the flow of plate current, that is, one in which, when the tube is operating with a direct plate voltage in series with a resistive load and a direct voltage control in the grid circuit, that the plate current cannot be extinguished by an adjustment of the grid bias. This is the 15 normal form of gaseous thermionic tubes and is the type commonly known commercially as Thyatron and Grid-Glow tubes.

Having fully described one embodiment of my invention in very specific detail, the generalities 20 and scope of the invention are set forth in the claims hereunder.

What I claim is:

1. The method of operating a normal gaseous thermionic tube which has a control electrode, 30 a cathode, and an anode, said tube having a plate resistance under cathode-current conduction independent of a first range of cathode-control-electrode-bias parameters when connected to a cathode-plate-voltage circuit having oscillatory 35 constants and having a negative resistance characteristic under a second range of cathode-control-electrode-bias parameter when connected to said circuit, which method comprises setting said parameters within said first range causing said 40 circuit to pass a non-oscillatory current and then setting said parameters within said second range causing said circuit to pass an oscillatory current.

2. The method of operating a normal gaseous thermionic tube which has a control electrode, a 45 cathode and an anode, which comprises subjecting said control electrode to connected circuits having parameters causing continuous conduction tube current and then subjecting said control electrode to connected circuits having oscillatory 50 parameters causing interruption of said current.

3. The method of operating a normal gaseous thermionic tube which has a control electrode with a predetermined voltage bias, a cathode, and an anode, which comprises causing said tube 55 to pass a continuous unidirectional current to a load circuit for an arbitrary duration of time, and then adjusting said bias causing said tube and said load circuit to provide oscillatory current which functions to extinguish said load current.

60 MONTFORD MORRISON.
